UNITED STATES PATENT OFFICE.

HENRY J. MCNEAL, OF WHEATLEY, KENTUCKY.

TRENCH-GUN SUPPORT.

1,195,055.

Specification of Letters Patent. Patented Aug. 15, 1916.

Application filed April 14, 1916. Serial No. 91,180.

To all whom it may concern:

Be it known that I, HENRY J. MCNEAL, a citizen of the United States, residing at Wheatley, in the county of Owen and State 5 of Kentucky, have invented new and useful Improvements in Trench-Gun Supports, of which the following is a specification.

This invention relates particularly to supports for guns, whereby the gun may be 10 mounted in position for operation and adjustment in a trench so as to adapt it to be raised for use and lowered for loading or other purposes, without the gunner being exposed to the enemy's fire.

15 The object of the invention is to provide a support for a rifle or like small arm by means of which the rifle may be supported for adjustment in the manner described and employed in conjunction with a periscope or 20 like observation device whereby the gunner may use the gun in an efficient manner without exposing himself.

A further object of the invention is to 25 provide a support which, while firmly holding the gun, adapts the gun to be raised, lowered, detached, and applied in a ready and convenient manner.

The invention consists of the features of 30 construction, combination and arrangement 35 of parts hereinafter fully described and claimed, reference being had to the accompanying drawings in which:—

Figure 1 is a sectional view through a trench showing the application of the invention, the gun appearing in projected position for use. Fig. 2 is a similar view showing the gun retracted for loading or other purposes. Fig. 3 is a top plan view of the device with parts appearing as shown in 40 Fig. 1. Fig. 4 is a rear elevation of the same. Fig. 5 is a vertical section on the line 5—5 of Fig. 2. Fig. 6 is a detail view of the pivoted shackle for connecting the stock of the gun with the swinging links. Figs. 7 45 and 8 are views showing a modified form of the invention.

In carrying my invention into practice, I provide a gun support comprising an anchoring member 1, which may be of the general form, as shown, of an ordinary gun stock. This anchoring member 1 is provided at its forward end with a spur 2 which is designed to be embedded in the earth of the wall of the trench 3 which faces in the direction of the enemy, and which of itself

may be of sufficient supporting capacity to sustain the weight of the desired device in use. In general practice, however, I prefer to provide the butt of the anchor stock 1 with a plate 4 to which is attached a rear 60 supporting device preferably consisting of a head 5 and a desired number of pivoted legs 6, which may be folded parallel with the anchor stock or swung downwardly at right angles thereto to rest upon the floor of the 65 trench, as shown in Figs. 1 and 2. When this is mounted the anchor stock 1 will be firmly held in position, but upon withdrawing the spur 2 and folding the legs 6 the support may be packed in close compass for 70 convenience, in storage and transportation.

Rising from the plate 4 is an upright 7 carrying at its upper end a socket member 8, and suitably attached to said upright and socket member is an observation device, such 75 as a periscope 9, which may be of any of the ordinary constructions in general use. This upright 7 and socket member 8 are stayed and reinforced from the forward portion of the anchor member 1 by bracing rods or 80 arms 10 carrying a stop member 11. A swinging carrier, composed of links 12, is mounted to swing between said braces 10 and downwardly and rearwardly between the sides of the uprights 7, and these links 85 are pivoted at one end to the neck portion of the anchor stock 1, as shown at 13, and carry at their opposite or free ends a jointed or pivoted shackle 14, said shackle being composed of sections 15 to adapt it to be opened and closed about the neck portion of the stock of the rifle or other small arm 16, said sections being detachably connected by a thumb screw 17, whereby they may be easily, 90 quickly and conveniently connected and disconnected for closing and opening movements.

In the use of the device, the gun 16 to be supported is fastened as described to the shackle 13 of the swinging links or carrier 12, whereby the gun is adapted to be swung upwardly and forwardly to a normally horizontal and projected position for use, as shown in Fig. 1, or swung downwardly and rearwardly until it is withdrawn at an angle 100 to the horizontal wholly or practically within the trench, so that it may be conveniently loaded, cleaned, repaired or detached, as occasion may require. When the gun is elevated for use the butt of the stock thereof 105 110 115

is fitted in the socket 8 and the weight of the gun maintains it in position, the forward motion of the gun being limited by contact of the links 12 with the stop 11. 5 The gunner may thereupon sight through the periscope 9, and operate the trigger of the gun in any preferred manner to discharge the same, the gunner being at all times entirely concealed within the trench 10 and protected from the fire of the enemy. When it is desired to withdraw the gun into the trench for loading or other purposes, the butt of the gun is grasped and pulled or tilted downward to withdraw it from engagement 15 with the socket, in which motion the gun tilts or swings upon the shackle as an axis, and then the gun may be drawn downwardly and rearwardly to the position shown in Fig. 2, in which operation it tilts 20 downwardly and rearwardly with the links 12. In this withdrawn or retracted position of the gun it will be to a large extent protected without detaching it from the support and may therefore be easily and conveniently 25 loaded by the gunner. The mode of detaching the gun and folding the support for transportation will be readily understood from the foregoing description.

In practice, the stock 1 and spur 2 may be 30 united by a hinge or pivot 2', so as to allow the gun support and gun to swing laterally in either direction on the pivot 2' as an axis of motion, without disturbing the relative positions of the other parts.

35 In some cases, as before intimated, the supporting leg 6 may be dispensed with, and such a modification is shown in Figs. 7 and 8. In this modification, also, the stop 11 is dispensed with and reliance placed entirely 40 upon the support of the gun in such a position that its barrel portion slightly overbalances its stock portion, which therefore is held by gravity tightly fitted within the socket 8.

45 In both forms of the invention, the socket 8 preferably consists of a back plate having a flange extending entirely around the same except at the bottom and forming a shallow elliptical receptacle, as will be readily understood. If desired the stop 11 may be 50 adjustable, in which event it is fitted to slide upon the braces 10 and provided with one or more set screws 11' to secure it in position, as will be readily understood.

I claim:—

1. A support for guns comprising an anchor member having a projection adapted to be embedded in the vertical wall of a trench, a swinging support for a gun mounted on said anchor member, and means adapted 60 when the gun is held elevated by said support for engagement with the gun to prevent upward movement thereof.

2. A device of the character described comprising an anchor member having an 65 earth engaging spur at one end thereof, a swinging carrier mounted on said anchor member and having means for engagement with a gun, and an upright provided with a 70 socket to receive the butt of the gun when in elevated position.

3. A device of the character described comprising an anchor member having an embedding spur projecting from one end thereof, a swinging carrier pivoted to said 75 anchor member, a shackle on said carrier to engage the stock of a gun, and an upright on the carrier provided with a holder to receive the butt of the gun.

4. A device of the character described 80 comprising an anchor member having an embedding projection at one end thereof, an upright provided with a gun butt receiving socket at the opposite end of said anchor member, a brace extending between the anchor member and socket, a swinging support carried by the anchor member and having a connecting member to engage the stock 85 of a gun, and a stop upon the brace for limiting the forward swinging movement of 90 said carrier.

5. A device of the character described comprising an anchor member having an embedding projection at one end thereof, a depending support at the opposite end of 95 said anchor member, an upright rising from the latter-named end of the anchor member and carrying a butt receiving socket at its upper end, a bracing element connecting said upright with the anchor member, and a 100 swinging support carried by the anchor member and provided with a pivoted shackle to engage the stock of a gun.

In testimony whereof I affix my signature in presence of a witness.

HENRY J. MCNEAL.

Witness:

JOE. WHITEHEAD.
